BOTTLE

Eugene R. Luedtke, Reedsburg, Wis., assignor to Hanks-craft Company, Reedsburg, Wis., a corporation of Wisconsin

Filed June 20, 1968, Ser. No. 12,452

Term of patent 14 years

Int. Cl. D9—01

U.S. Cl. D9—129

Fig. 2

Fig. 1

Fig. 3

Fig. 4

FIG. 1 is a bottom perspective view of a bottle, showing my new design;

FIG. 2 is a side elevational view on a reduced scale; FIG. 3 is a top plan on the same scale as FIG. 2; and FIG. 4 is a bottom plan view on the same scale of FIG. 2.

I claim:

The ornamental design for a bottle, as shown.
